UNITED STATES PATENT OFFICE

JOHN F. O'CONNOR, OF CHICAGO, ILLINOIS, ASSIGNOR TO W. H. MINER, INC., OF CHICAGO, ILLINOIS, A CORPORATION OF DELAWARE

SHOCK-ABSORBING MECHANISM

Application filed September 6, 1927. Serial No. 217,809.

This invention relates to improvement in shock absorbing mechanisms.

One object of the invention is to provide a shock absorbing mechanism of high capacity

5 specially adapted for railway draft riggings, including relatively movable follower members and interposed laminated spring means in the form of disc members of channel shaped section.

10 Another object of the invention is to provide a shock absorbing mechanism comprising relatively movable follower members and spring resistance means interposed between said follower members, including a main 15 spring resistance co-operating with spring followers, and auxiliary spring resistance means of lesser capacity interposed between the spring followers and the main followers, adapted to be compressed during the initial 20 portion of the compression stroke, together with positive stop means limiting the compression of said auxiliary spring resistance means.

In the drawings forming a part of this 25 specification, Fig. 1 is a horizontal sectional view of a portion of a railway draft rigging illustrating my improvements in connection therewith. Fig. 2 is a vertical transverse sectional view corresponding substantially to the line 2—2 of Fig. 1. Fig. 3 is a longitudinal vertical sectional view of the front end portion of another embodiment of my invention corresponding substantially to the line 30 3—3 of Fig. 4; and Fig. 4 is an end elevational view of the mechanism illustrated in 35 Fig. 3.

In said drawings, referring first to the embodiment of the invention illustrated in Figures 1 and 2, 10—10 indicate channel shaped 40 center sills of a railway car underframe, to the inner sides of which are secured the usual front stop lugs 11—11 and rear stop lugs 12—12. The rear end portion of the draw-bar is designated by 13, to which is operatively connected a yoke 14, of well known form. The shock absorbing mechanism proper, a front main follower 15 and a rear main follower 16 are disposed within the yoke, the yoke in turn being supported in operative position by a detachable saddle plate 17 secured

to the draft sills. A pair of guide members 18 are also secured to the inner sides of the draft sills to properly center the shock absorbing mechanism between the sills.

The improved shock absorbing mechanism 55 illustrated in Figures 1 and 2 comprises broadly front and rear follower casings A and B; a pair of spring followers C—C; a main spring resistance D; front and rear auxiliary spring resistance members E—E; and 60 a retainer bolt G.

The front and rear follower casings A and B are substantially in the form of box-like members, each having a cylindrical central opening 19, and outer end walls 20. The end 65 walls 20 co-operate with the front and rear followers 15 and 16, respectively, having flat bearing thereon. The follower casing A has the central bore 19 thereof enlarged at the rear end, as indicated at 21 and telescopically 70 receives a cylindrical extension 22 on the rear follower casing B. The casings are so proportioned that relative approach of the same will be limited by the front end of the cylindrical portion 22 of the casing B coming into 75 engagement with the end wall of the opening 21 of the casing A, and the rear end of the extension of the casing A coming into abutment with the shoulder at the inner end of the cylindrical portion 22 of the casing B. 80 Each of the casings A and B is provided with an inwardly extending central hollow boss 23 formed integral with the end wall 20 of the corresponding casing.

The spring resistance means comprises the 85 central main spring resistance D and front and rear auxiliary spring resistance elements E—E. The spring followers C—C, which are in the form of relatively heavy discs, are interposed between the spring resistance D 90 and the auxiliary spring resistance members E—E. As most clearly shown in Fig. 1, the spring followers are normally spaced from the inner ends of the enlargements on the front and rear casings A and B, the enlargements 95 23 acting as pressure transmitting posts to limit relative movement of the casings and the spring followers. The spring resistance D comprises a plurality of disc-like members, each of the disc-like members 100

being provided with a central opening adapted to freely accommodate the retainer bolt G. The body portion of each disc-like plate between the periphery thereof and the central perforation is curved in cross-section, as clearly shown in Fig. 1. In other words, each spring plate is in the form of a dished annular member. The discs forming the spring resistance D are so arranged that two adjacent members have the concave surfaces of the dished portion opposite, so that there is contact between the same at two spaced annular zones, one contact zone being at the peripheries of the discs and the other zone near the central portion thereof. The convex outer surfaces of the pairs of discs are in face to face contact thus providing bearing contact on an annular zone.

The auxiliary spring resistance members E also comprise a plurality of plate-like members, in the form of dished rings. In other words, each spring plate of the auxiliary spring resistance members E is in the form of a channel shaped ring. The ring members of each spring resistance E are arranged in pairs, the members of each pair having the concave faces thereof opposed thereby providing bearing contact at two spaced annular zones, one zone being at the peripheries of the rings and the other along the edges at the openings of the rings. As shown, the outer convex surfaces of adjacent pairs are in abutment, thereby providing bearing engagement on an annular zone. As most clearly shown in Fig. 1, the ring members of the spring resistance elements E surround the bosses or posts 23 of the front and rear follower casings A and B, the openings in the ring members being of such a size as to freely accommodate the posts 23.

The mechanism is held assembled and of over-all uniform length by the retainer bolt G, which has its opposite ends anchored within the bosses or posts 23 of the front and rear follower casings A and B. The bolt is so adjusted as to place both the spring resistance D and spring resistance members E under initial compression.

The operation of my improved shock absorbing mechanism, as illustrated in Figures 1 and 2, assuming a compression stroke, is as follows: The casings A and B will be moved relatively toward each other upon relative approach of the main followers 15 and 16 thereto, compressing the spring resistance elements D and E. The spring resistance elements E are of lesser capacity than the spring resistance D, and consequently will be compressed to a greater extent than the spring resistance D during the first part of the compression stroke. The compression of the spring members E and D during the relative approach of the main followers A and B will continue until the spring followers C—C are engaged by the posts 23, whereupon fur-

ther compression of the auxiliary spring resistance elements E will be prevented and the main spring resistance D will be compressed between the spring followers C during the remainder of the compression stroke. The described action will continue either until the actuating force is reduced, or movement of the follower casings A and B is limited by engagement of the inner ends of the same. During release, upon the actuating force being reduced, the expansive action of the spring resistance elements D, E and E will restore all of the parts to a normal position, outward separation of the casings A and B being limited by the retainer bolt G.

Referring to the embodiment of the invention illustrated in Figs. 3 and 4, the same comprises broadly front and rear follower casings H and K of hollow box-like form provided with a cylindrical bore. As most clearly shown in Fig. 4 the casings are provided with interengaging arm-like extensions 30—30, the front follower casing H being provided with said extensions on the opposite sides thereof, while the rear casing is provided with the extensions 30 at the top and bottom sides thereof. The extensions 30 of the front and rear follower casings interengage and are provided with beveled meeting faces as most clearly shown in Fig. 4. The spring resistance means M, comprising a plurality of disc-like plate members, is disposed within the casings H and K and has bearing on the end walls of the casings. The disc-like members M are of substantially the same design as the disc-like members D described in connection with the first form of the invention, with the exception that they are not provided with central perforation.

The mechanism is held of over all uniform length and maintained assembled by retainer bolts N, which are disposed at the four corners of the casings, the casings being provided with longitudinal bores to receive the shanks of the retainer bolts N. The operation of the improved shock absorbing mechanism illustrated in Figs. 3 and 4, is substantially the same as that hereinbefore described in connection with Figs. 1 and 2, with the exception that there is no preliminary spring action, the entire set of discs, comprising the main spring resistance N, being compressed throughout the compression stroke of the mechanism.

As most clearly shown in Fig. 2, the casings A and B, employed in connection with the embodiment of the invention illustrated in Figs. 1 and 2 may be provided with openings 31 at the four corners thereof to avoid heavy section of metal at these points. It will be evident that when the central bolt G is omitted discs of the type shown in Figs. 3 and 4 may be employed in place of the perforated discs D illustrated in Figs. 1 and 2.

While I have herein shown and described what I now consider the preferred manner of

carrying out my invention, the same is merely illustrative, and I contemplate all changes and modifications that come within the scope of the claims appended hereto.

I claim:

5 1. In a shock absorbing mechanism, the combination with relatively movable main follower casings having cylindrical interior spaces, one of said casings having a cylindrical end section telescoped with the inner end of the other casing; of spring followers interposed between said main followers; a spring resistance comprising a plurality of co-acting ring shaped spring plate elements interposed between said spring followers and fitted within said spring spaces; additional spring resistance means interposed between the spring followers and main followers; and abutment means on said main followers co-operating with the spring followers for limiting relative movement of said main and spring followers.

2. In a shock absorbing mechanism, the combination with front and rear follower casings having central interior abutment posts thereon; of laminated spring ring members within said casings, said ring members surrounding the abutment posts; front and rear spring followers co-operating with said laminated members, said spring followers being normally spaced from the posts and engaged thereby before full compression of the mechanism; and a main spring resistance interposed between said spring followers.

35 In witness that I claim the foregoing I have hereunto subscribed my name this 3rd day of September, 1927.

JOHN F. O'CONNOR.
